UNITED STATES PATENT OFFICE.

MEYER KRAMER, OF NORWAY, MICHIGAN.

DESIGN FOR A ROCK-DRILL.

SPECIFICATION forming part of Design No. 29,296, dated August 30, 1898.

Application filed August 5, 1898. Serial No. 687,865. Term of patent 14 years.

To all whom it may concern:

Be it known that I, MEYER KRAMER, a citizen of the United States, residing at Norway, in the county of Dickinson and State of Michigan, have invented a new and useful Design for a Rock-Drill, reference being had to the accompanying drawings, forming a part thereof.

In the accompanying drawings, Figure 1 is an elevation of a drill embodying my design, and Fig. 2 a plan view of the same.

The leading feature of my design consists in a body portion having four wing-shaped projections with inverted-V-shaped surfaces and a nipple portion provided with wing-shaped projections having inverted-V-shaped upper surfaces.

A is the body portion; B B, the wing-shaped projections on the body portion; b, the inverted-V-shaped upper surfaces; C, the nipple, provided with the V-shaped upper surfaces c, the whole presenting to the eye a harmonious and ornate figure, as shown in the accompanying drawings.

I claim—

The design for a rock-drill, substantially as shown and described.

MEYER KRAMER.
